MOLD FOR ICE CREAM OR THE LIKE

Ben Edward Rasmusson, 915 1st S.,
Kent, Wash. 98031

Filed July 24, 1968, Ser. No. 12,869

Term of patent 14 years

Int. Cl. D7—99

U.S. Cl. D44—1

I claim:

The ornamental design for a mold for ice cream or the like, as shown.
